VALVE MECHANISM FOR GAS-ENGINES.

1,110,921.

Specification of Letters Patent. Patented Sept. 15, 1914.

Application filed September 21, 1912. Serial No. 721,698.

To all whom it may concern:

Be it known that I, WILLIAM A. GILL, a citizen of the United States, and a resident of Portland, county of Multnomah, and State of Oregon, have invented a new and useful Improvement in Valve Mechanism of Gas-Engines, of which the following is a specification.

This invention relates to the valve mechanism of internal combustion engines of the four-cycle type.

The purposes of my invention are as follows: to eliminate any spring control action of the valve, and to use a slide valve mechanism positively driven, of simple construction, adapted to allow for expansion without sacrificing gas-tight fit; also to provide for a constant gas-tight fit of the valves, by automatically regrinding them to the surface of the chamber on which they are seated, and by providing means effecting an automatic take-up as the valves are worn in service; also to provide for constant, automatic, effective lubrication, and to render the valve action practically noiseless, and to provide valve operating means including a fixed shaft and bell crank and link connections adapted to be positioned on the approximate dead-center when the explosion occurs. I attain these and other incidental features by means of the mechanism illustrated in the accompanying drawings, in which:

Figure 1 is a vertical longitudinal section of a four-cycle vertical gas engine embodying my invention; Fig. 2 is a sectional front elevation of the valve mechanism of a gas engine showing the relative position assumed by the various parts at the beginning of the first phase, that is, when the piston reaches the upper end of its exhaust stroke, the exhaust valve just closing and the inlet valve about to commence opening; Figs. 3, 4 and 5 are views similar to Fig. 2, showing the valve mechanism in different phases of its action, as follows, viz: Fig. 3 shows the parts positioned during the first phase, that is, at a point during the intake or charging stroke, the intake port being opened and the piston going down; the piston in this case being positioned about midway in its cylinder on its downward stroke; Fig. 4 shows the approximate position of the valve mechanism when the piston is at the beginning of its explosion stroke; Fig. 5 shows the parts positioned in their last phase, that is, at the

end of a cycle of motion of the valve members and the operating mechanism thereof; the exhaust port for scavenging the burned gases from the cylinder is shown opened, such opening being effected during the interval that the piston is rising, and the piston (not shown) is positioned approximately midway in its cylinder on its upward stroke; Fig. 6 is a detailed perspective view of the parts constituting the valves and the stems of my device, the parts being shown as separated, but relatively connected by broken lines; Fig. 7 is a section on line A—A of Fig. 1; and Fig. 8 is a bottom view of one of the sliding valves showing the arrangement of the slot in which the valve stem bears.

I am aware that positively driven piston valves have heretofore been used, but in all such cases no provision was made for taking up the wear, which invariably occurs both on the inner walls of the casing and the outer surface of the valves, without the use of "snap rings." Furthermore, since allowance for expansion must be made in valves of the type referred to, it is very difficult to secure a gas-tight fit. Another objection to said valves was that efficient lubricating means have not been provided. These objections have been overcome in my improved valve mechanism, described as follows: The gas engine, *a*, is of the usual construction, embodying a cylinder chamber *a*², in which reciprocates a piston *b*, driving a crank *c*, integral with the driven or engine shaft *c*'. My valve mechanism is actuated by a pair of two to one meshing gears *d* and *e*, which rotate a valve crank shaft *f*. The latter has a pair of crank-arms *g* and *h*, the crank arm *g* being positioned a quarter of a revolution ahead of the crank arm *h*. Above and to one side of the valve operating crank shaft, *f*, is located a fixed shaft *i*, on which is fulcrumed a pair of bell crank levers or rocker arms, *j* and *k*, connected to the crank-arms *g* and *h* of the valve shaft by the links *m* and *n* respectively. To the rocker arms *j* and *k* are further attached the links *o* and *p*, which are connected to the valve stems *q* and *r* respectively for actuating the valves. Said rocker arms are so arranged that the wrist pins, *j'*, *k'*, will be moved a quarter of a circle during each revolution of the crank-shaft *f*. The extreme uppermost and lowermost positions of the wrist pin *j'* are shown by the dotted circles *j''* and *j'''*, respectively,

in Fig. 1. The wrist pin k' has the same relative movements as the pin j' . The pivotal connections between the ends of the links, m , o , n , p , and the rocker arms are so located with respect to the fulcrum of the latter as to impart to said link ends equal angular displacement but unequal angular velocity, to thereby give to the valve member or members a non-uniformly varying motion so timed as to cause the movement of the valves to be retarded during the interval the valves are positioned to entirely close or entirely open the inlet or exhaust ports of the valve chamber, and accelerated during the interval the valve members are so positioned as to partially uncover said ports; that is to say, as when the ends of the valves have traveled approximately to the point of starting to uncover or to cover the ports. The object of the described valve motion is to cause a quick opening and closing of the valve ports, and particularly to avoid the so-called "wire drawing" effect in the opening and closing of the valves. It will be noticed that the fixed shaft i is aligned with the common center of mechanism of the valve. The object of this particular location of said fixed shaft is this: When the explosion occurs, the connecting parts between said fixed shaft and the valves will be approximately on a dead center, thereby causing the shock of such explosion to be mostly taken up by the fixed shaft i , instead of having it transferred to the valve crank-shaft f , which would necessitate a much heavier construction of the latter. On the valve-stems, q and r , are mounted the reciprocating or sliding valves, s , t , in such manner that the valves may have a slight lateral play, as apparent from Fig. 6. To this end the valve-stems q and r are made with reduced portions, q^2 , r^2 , near the top, so as to be free to move laterally from the heads q' , r' , which may be inserted in the slots s' , t' , at the base of the valves. The valves, s , t , reciprocate within a valve chamber, x , the latter being provided with two openings y and z , each extending nearly half way around the chamber, of which y constitutes the exhaust port and z the intake port. The valves, s , t , are approximately semicylindrical, their flat faces being adapted to slide against each other. The valves s , t , may be said to be members of a valve unit. A plate u , inserted in the groove v of the valve s , is forced continually outward by the springs w , so as to cause the outer or cylindrical faces of the two valves to bear constantly against the walls of the valve chamber, x , thereby automatically taking up any wear, as well as maintaining a gas-tight joint between the inner faces of the two valves. The bottom of the valve chamber x is closed by a cylindrical head 1 and constitutes an oil reservoir, and the valves

dip in the oil in their down position. The oil is drawn into the chamber x from the reservoir 6, in the base of the crank case a' , through a tube 2. Said tube is provided with a check-valve at 3 which permits a flow in an upward direction only. The oil is drawn up into the chamber x by the upward movement of the valves, and overflows through the stand pipe 4, as obvious; during the downward movement of the valves the oil in the bottom of the valve chamber is forced up, thus insuring an efficient lubrication of the valve mechanism.

The plate, u , in fact performs the same functions as a piston ring; but when the explosion occurs, the gas which will have penetrated between the flat faces of the valves will drive them still more forcibly against the walls of the chamber x , thereby insuring a perfect gas-tight contact, and tending to automatically regrind the valves during the movement of the latter following each explosion.

I claim:

1. In a valve mechanism, a valve chamber, two approximately semicylindrical valves reciprocating in such chamber; means for operating the valves; and means for preventing the passage of gas between the inner faces of the valves, said means adapted to hold said valves against their seats. 90

2. In a valve mechanism, a valve chamber, two approximately semicylindrical valves reciprocating in such chamber, the inner faces of such valves adapted to slide against each other, means for operating the valves, and means for preventing the passage of gas between the inner faces of the valves, said last mentioned means adapted to hold said valves against their seats. 100

3. In a valve mechanism, a valve chamber, two approximately semicylindrical valves reciprocating in such chamber side by side; means for operating the valves; a plate movably seated in the inner face of one of said valves and adapted to bear on the opposed face of the other valve; and means for causing said plate to bear constantly against the opposed face of the other valve. 110

4. In a valve mechanism, a valve chamber, two approximately semicylindrical valves reciprocating in said chamber side by side; means for operating the valves; means for preventing the passage of gas between the inner faces of the valves; said means adapted to hold said valves against their seats; valve stems; and means for connecting the stems with the valves adapted to permit the latter lateral movement. 115

5. In a valve mechanism, a valve chamber, two approximately semicylindrical valves reciprocating in said chamber side by side; means for operating the valves; a plate movably seated in the face of one of said valves and adapted to bear on the opposed face 125

of the other valve; means for causing said plate to bear constantly against the opposed face of the other valve; valve stems; and means connecting the stems with the valves adapted to permit the latter lateral movement.

6. In a valve mechanism, a valve chamber, two approximately semicylindrical valves reciprocating in said chamber side by side; means for operating the valves; a spring-controlled plate movably seated in the inner face of one of said valves and adapted to bear on the opposed face of the valve; valve stems; and means connecting the stems with the valves adapted to permit the latter lateral movement.

7. In a valve mechanism, a valve chamber, two approximately semicylindrical valves reciprocating in said chamber side by side; means for operating the valves; a plate movably seated in the inner face of one of said valves and adapted to bear on the opposed face of the other valve; means for causing said plate to bear constantly against the op-

posed face of the other valve; valve stems formed with heads; said valves provided with recesses for receiving said stem heads.

8. In a valve mechanism, a valve chamber, piston-like valves, and means for actuating the latter; the bottom of the valve chamber adapted to hold lubricating oil and provided with an inlet for the latter, and an outlet for removing the oil overflowing a predetermined level, whereby the action of the valve operates as a suction feed for the lubricating oil, and the lubrication of the valve is automatically effected.

9. In a valve mechanism, a valve chamber, two piston-like valves reciprocating in such chamber side by side; means for operating the valves; and means for preventing the passage of gas between the inner faces of the valves, said means adapted to hold said valves against their seats.
